UNITED STATES PATENT OFFICE

JAMES F. HENDERSON, OF DETROIT, MICHIGAN, ASSIGNOR TO DETROIT RIVER IRON WORKS, OF DETROIT, MICHIGAN, A CORPORATION OF MICHIGAN

HOISTING MECHANISM

Application filed October 30, 1925. Serial No. 65,750.

To manipulate various kinds of loads by swing-derrick or swing boom cranes, portable steam derricks, cable hoists and conveyor, and other types of hoists, it is necessary 5 to control a plurality of cables, and for this purpose I have put into practice a hoisting mechanism including a plurality of drums which may be selectively driven and controlled by a compact and durable power transmission mechanism and brake drum and lever arrangement.

Without confining my invention to any specific use, the construction of the hoisting mechanism will now be described by aid of 15 the drawings, wherein

Figure 1 is a front elevation of the hoisting mechanism;

Fig. 2 is a horizontal sectional view taken on the line II—II of Fig. 1;

20 Fig. 3 is a cross sectional view taken on the line III—III of Fig. 1, showing the drive control means, and

Fig. 4 is a similar view taken on the line 25 IV—IV of Fig. 1, showing the brake control means.

The hoisting mechanism includes a bed frame 1 and mounted on one end thereof is a conventional form of steam engine 2 representing a suitable source of power. The 30 engine has been shown as having a control valve 3 operatively connected by a link 4 to a crank 5 on a rock shaft 6. This shaft is journaled in bearings 7 of the bed frame and is provided with a lever 8 so that the shaft may 35 be easily rocked to actuate the valve 3 and control the operation of the engine 2.

Mounted on the bed frame 1 are A-frames 9 provided with bearings 10 for a longitudinally disposed driven shaft 11 which has one 40 end thereof provided with a large gear wheel 12 meshing with a gear wheel 13 on the drive shaft 14 of the engine 2, and obviously the shaft 11 might be driven by an electric motor substituted for the engine 2.

45 The A-frames 9 are provided with longitudinally alining bearings 15 and fixed in said bearings is a longitudinal shaft 16. Rotatable on this shaft are hoisting drums 17 and each hoisting drum has a brake drum 18 at one end thereof and a large gear wheel 19 at

its opposite end. It is to the hoisting drums 17 that cables may be attached and wound thereon for controlling the movement of a load or load carrier.

55 Meshing with the large gear wheels 19 of the drums 17 are small gear wheels 20 loose on the driven shaft 11 and each small gear wheel has a clutch face or member engageable by a clutch 21 at the side of said gear wheel. The clutches 21 are slidably keyed on the driven shaft 11 and adapted to rotate therewith and at times couple the gear wheels 20 to the driven shaft to establish rotation of the hoisting drums 17 by the driven shaft 11. The clutches 21 are operatively engaged by 60 yokes 22 of bell cranks 23 pivotally mounted on the bed frame 1. The bell cranks 23 are connected by links 24 to the lower ends of levers 25 which extend upwardly in front of the drums and are pivotally supported by a 65 longitudinally disposed bracket 26 connecting the A-frames 9.

65 The clutch yokes 22 are connected by coiled retractile springs 27 to the bracket 26 and these springs are positioned so that the 70 clutches will be held either engaged or disengaged relative to the small gear wheels 20. The horizontal sectional view shown in Fig. 2 has been taken below the springs 27, but one 75 of the springs has been indicated by dotted lines to show how it will be swung from one side of a bell crank pivot to the other side whereby its retractile force may hold the bell crank in either position to maintain the clutch either in or out, thus permitting an attendant 80 of the hoisting machine setting a clutch by manipulation of one of the levers 25 and devoting his attention to other levers. As an instance of such use may be mentioned that 85 of raising a load suspended from a boom 90 while the boom is laterally swung in a desired direction, thus necessitating two of the hoisting drums 17 being driven in synchronism.

95 On the bracket 26, adjacent each brake drum 18, is a bearing 28 and pivotally connected to said bearing is a shackle 29 of a brake band 30 which extends over and about the brake drum 18, as best shown in Fig. 4. The brake band has a conventional 100 form of shoe 31 and said brake band is pro-

vided with a shackle 32 to which is pivotally connected a rod 33, said rod extending forwardly from under the brake band and through an opening 34 in the bracket 26. On the outer screwthreaded end of the 5 rod 33 are nuts or abutments 35 with the innermost abutment engaged by the convex face 36 of a rod shifting member 37 through which the rod 33 extends. The rod shifting member 37 is pivotally connected to the bracket 26, as at 38, and the upper end of said rod shifting member is pivotally connected by a link 39 to the lower angular end of a lever 40. This lever is pivotally connected 10 to the bearing 28 and extends upwardly in front of the machine.

Encircling the rod 33, between the shackle 32 and the bracket 26, is a coiled expansion spring 41 and the expansive force of this 15 spring is adapted to release the brake band relative to the brake drum, when the lever 40 is in a "brake released" position. The expansive force of the spring 41 also assists in retaining the lever 40 in a "brake applied" 20 position. This is brought about by the toggle arrangement of the lever 40 and link 39 relative to the rod actuating member 37. As shown in Fig. 4 the brake band is applied and the expansive force of the spring 25 41 maintains the pivotal connection 42 of the link and lever below the plane of the lever pivot 43 and the link pivot 44. In this position the expansion spring 41 tends to draw the rod 33 and the upper pivot point 30 44 on the member 37 inwardly towards the drum. Such movement however is very slight and is limited by the lower end of the lever 40. Nevertheless the spring action is 35 a force which maintains the pivot point 42 below a line connecting the pivot points 43 and 44, and this relation of the pivot points determines the applied position of the brake. The toggle is broken upwardly by pushing the upper end of the lever 40 towards the 40 45 brake drum, whereupon the pivot 42 assumes a position above a line connecting the pivots 43 and 44. This relative position of the several pivot points determines the release position of the band on the brake drum, and 50 this position is maintained by the expansive force of the spring 41 which draws the pivot point 44 towards the point 43 and prevents the point 42 from dropping.

While the hoisting mechanism may be 55 used for various purposes, it has been especially designed for "sand suckers," a type of river vessel provided with an outboard boom supporting a sand sucking pipe having a nozzle or head that is lowered to the bottom of the river to obtain sand therefrom. The sand pipe and its nozzle are supported at intervals along the boom so that the nozzle end of the pipe may be lifted from time to time and the boom swung so that 60 65 the nozzle may be placed in another po-

sition for obtaining sand. The manipulation of the sand pipe can be easily performed by my hoisting mechanism and I attach considerable importance to the fact that all of the hoisting drums and brake drums are coaxially of one another on a common longitudinally disposed shaft support. This arrangement is considered very compact and advantageous on the deck of a vessel compared to individual hoisting drums otherwise arranged, and it is obvious that a single attendant of the hoisting machine may readily control all of the levers in one position, since the levers are in proximity to each other and may be individually set whereby the attendant may safely leave one lever to actuate another.

It is thought that the operation and utility of the hoisting mechanism will be apparent without further description, and while in the drawings there is illustrated a mechanism which has gone into general use, yet I would have it understood that the construction is susceptible to such changes as are permissible by the appended claim.

What I claim is:—

In a brake, a drum, a brake band about said drum, a fixed bracket having one end of said band connected thereto, a rod extending laterally through said bracket under said brake drum and connected to the remaining end of said brake band, a lever pivotally supported from said bracket, toggle levers operatively connecting said lever to said rod and adapted in one position to maintain said brake band applied, and means on said rod engaging said bracket adapted to either maintain the toggle levers with the brake band applied or retain said brake band in released relation to said brake drum.

In testimony whereof I affix my signature.
JAMES F. HENDERSON.
